CLAIM

The ornamental design for an adjustable floor chair, as shown.

DESCRIPTION

FIG. 1 is a perspective view from above illustrating the top and left side of an adjustable floor chair;

FIG. 2 is an elevation view of the front of the adjustable floor chair of FIG. 1;

FIG. 3 is an elevation view of the back of the adjustable floor chair of FIG. 1;

FIG. 4 is an elevation view of the left side of the adjustable floor chair of FIG. 1;

FIG. 5 is an elevation view of the right side of the adjustable floor chair of FIG. 1;

FIG. 6 is a plan view of the top of the adjustable floor chair of FIG. 1; and,

FIG. 7 is a plan view of the bottom of the adjustable floor chair of FIG. 1.

Where applicable, elements are shown in broken lines herein for illustrative purposes only, and form no part of the claimed design.

1 Claim, 7 Drawing Sheets
